TYPEWRITING MACHINE

William F. Metzger, Queens Village, N. Y., assignor to Royal Typewriter Company, Inc., New York, N. Y., a corporation of New York

Application June 3, 1938, Serial No. 211,644

22 Claims. (CL 197—63)

This invention relates to typewriting machines and more particularly to stops for arresting or limiting movement of typewriter carriages in letter-spacing or return directions and mechanism for adjustably positioning such stops.

It is usual to provide cooperating stop elements on typewriter main frames and carriages for arresting or limiting movement of the carriages either for fixing the writing margins or for positioning the carriage for tabulating operations. Stops and stop-setting mechanism embodying the present invention are especially suited for use in fixing the margin on the typed sheet and the embodiment of the invention to be described comprises a typewriter including a stop arranged to cooperate with a stop on the frame for fixing the left-hand margin of the typed sheet and mechanism for adjustably positioning one of the cooperating stops. It will be understood, however, that the invention is adapted for more general application.

An object of the invention is to provide an improved form of adjustable stop for arresting or limiting movement of a typewriter carriage on the associated frame in letter-spacing direction.

Another object is to provide mechanism cooperable with an adjustable stop for quickly and easily moving the stop along its support and automatically setting it in adjusted position.

A further object is to provide mechanism of the character referred to which is of simple construction, easy to operate, and certain in its action in correctly positioning the stop.

Other objects will become apparent from a reading of the following description, the appended claims and the accompanying drawings, in which:

Figure 1 is a fragmentary front elevational view of a typewriter carriage, showing parts of mechanism embodying the invention as viewed when looking in the direction of the arrows 1—1 in Figure 3;

Figure 2 is a front view drawn on an enlarged scale, some parts of the carriage being omitted, and with stops and stop setting mechanism, shown partly in elevation and partly in section;

Figure 3 is an enlarged view in vertical cross section on the line 3—3 of Figure 2;

Figure 4 is a detail sectional view taken on the line 4—4 of Figure 5 and drawn on an enlarged scale;

Figure 5 is a horizontal sectional plan view looking in the direction of the arrow 5 in Figure 6;

Figure 6 is a longitudinal and vertical sectional view with parts shown in elevation and looking in the direction of the arrow 6 in Figure 5;

Figure 7 is a detail cross sectional view on the line 7—7 of Figure 2;

Figure 8 is a detached perspective view of one form of stop setting rod; and

Figure 9 is a similar view of a modified form of stop setting rod.

The drawings show only such of the usual parts of a typewriter as are necessary in order to make clear the manner of applying stops and stop-setting mechanisms embodying the invention to typewriters generally. The known or usual parts thus shown are of the form used in the Royal portable typewriter and include main-frame-mounted tracks A—A, a main frame rear wall part B, and a carriage C having a base 1 formed with tracks 2 supported for letter-spacing and return movements on the tracks A—A by means of ball bearings 3. A platen or cylinder 4 is mounted for rotation between end plates 5 and 6 forming part of the carriage structure, and a paper pan 7 supported on a bracket 8 extends under and in rear of the platen. A paper table 9 is pivotally mounted on an end plate connecting bar 10, being adapted to be aligned with a paper pan scale 11 as shown in full lines in Figure 3 and to be swung upwardly and rearwardly to 30 the position shown in dotted lines in Figure 3 for rendering the stop mechanism accessible. Brackets 12—12 on the carriage base serve to mount a platen scale 13 in front of the platen and brackets 14—14 connected to the front frame 15 track A mount a stationary scale 15. A center stop 16 of known kind is shown as being pivotally mounted as at 17 on the frame wall B, a line lock lever 18 being pivotally mounted as at 19 on the center stop, also in a known manner.

In accordance with the disclosed embodiment of the invention, a stop is supported and locked in adjusted position on the carriage for cooperation with the frame-mounted center stop 16 to arrest or limit movement of the carriage and means are provided for quickly and easily unlocking the stop, shifting it along its support to adjusted position, and for automatically re-locking the stop in adjusted position on the support when the stop engages and is pushed against the 50 center stop 16.

In the form shown, left and right-hand margin stops, respectively designated D and D', are mounted on a margin stop bar E having transverse teeth 20 spaced along its lower face and 55

being formed with a slot 21 extending upwardly from the bottom or toothed face of the bar, the bar being supported on and between the carriage end plates 5 and 6; and a stop setting rod generally designated F is mounted for sliding movements in the slot 21, extending out through the end plate 5. In order to support the left-hand end of the bar E on the end plate 5 without obstructing the slot 21, a clip 22 formed with prongs 23—23 extending into recesses 24—24 in the bar is secured to the end plate 5 by a screw 25 and by partial embracement of the end plate connecting bar 10. The right-hand end of the margin stop bar is secured to the end plate 6 by means of a screw 26.

The left margin stop D includes an inverted U-shaped member 27 mounted for sliding movement on the stop bar E, the downwardly extending legs of the member 27 being connected by pins 28 extending across and under the bar E. A leaf spring 29 mounted on the pins presses upwardly against the teeth 20, serving to seat the top part of the member 27 on the bar. The U-shaped member is formed with an extension 30 bent laterally as at 31 and adapted to engage the center stop 16 when the carriage is moved to the right for fixing the left-hand margin on the sheet being typed.

The stop element D is provided with a latch 32 formed with mounting ears pivoted on the right end pin 28 as viewed in Figures 2 and 6. The left-hand end of the latch 32 is turned downwardly as at 34, the downwardly turned end portion 34 being recessed as at 35 so as to receive the margin stop bar E, the formation of the recess providing a latch cross bar or nose 36 extending across the slot 21 and being engageable between adjacent teeth 20. A spring 37 bearing upon the top of the U-shaped member 27 and seated in a recess 38 in a finger knob 39 on the latch urges the latch upwardly and thus urges the nose 36 into engagement with the toothed bar E. Thus, when the latch is in the position shown in Figure 2, the stop element D will be held against longitudinal movement relative to the bar E and the carriage, so that when the carriage is moved to the right, engagement of the extension 30 on the U-shaped member 27 with the center stop 16 will prevent further movement of the carriage to the right, thus fixing the right-hand margin in accordance with the setting of the stop element D on the bar E. Preferably, the stop element D is provided with an adjustably mounted gauge 40 which may be formed with a slot 41 through which is passed the shank of a screw 42 having threaded engagement with the latch 32, the gauge being formed with a pointer 43 directed towards the scale 11.

In accordance with the invention the rod F is arranged to cooperate with the stop D for adjustably positioning the stop on the bar E for varying or determining the left-hand margin on the work sheet. As shown, the rod comprises a main portion or shank 44 mounted for sliding movements within the slot 21 in the bar E, the main portion extending from the bottom of the slot not quite to the roots of the teeth 20, so as not to overlap the tooth interspaces. The left-hand end of the rod extends through the end plate 5 and is provided with an operating handle 45, engagement of which with the end plate 5 limits movement of the rod F to the right. The rod is formed adjacent its right-hand end with an enlargement 46 provided with an inclined cam edge 47 and with a transverse recess form-

ing a seat 48 adjacent the cam edge, the seat having inclined walls 48^a and 48^b. The right-hand end of the rod F is provided with a strap 49 comprising a bottom 50 which extends across the bottom of the rod E, sides 51 which extend up alongside the sides of the bar E, and top portions 52 which are turned over to lie along the top of the bar E.

In operation, and assuming that the parts are in the positions shown in Figure 2 and that it is desired to position the stop D adjustably in any set position, the handle 45 is grasped and the rod F is drawn to the left until the cam edge 47 engages the latch nose 36. In some instances, the frictional engagement of the spring 29 and U-shaped member 27 with the bar E may restrain the stop element D against movement to the left when the latch nose is engaged by the cam 47. Further movement of the rod F to the left will cam the latch nose downwardly, after which the latch nose will drop into the seat 48. The opposed side walls 48^a—48^b of the seat 48 are inclined on a somewhat steeper slope than the cam edge 47, the slope of the side wall 48^a being such that the urge of the latch spring 37 will be sufficient to connect the stop element D releasably and frictionally to the rod F when the rod is moved to the right. The carriage will then be moved to the position at which it is desired it shall be arrested during return movements to fix the left-hand margin, this position being determined by reference to registration of the pointer 53 on the type bar guide 15 with the proper scale designation on the cylinder scale 13. Then, to set the margin stop element D, the rod F is pushed to the right as viewed in Figures 1 and 2 until the extension 30 engages the center stop 16. Continued movement of the rod F to the right will then cause the side wall 48^a of the seat 48 to cam the latch nose downwardly, displacing it from the seat 48 and permitting it to ride up the inclined cam edge 47 and thereafter to engage between two adjacent teeth 20 on the bar E, thereby locking the stop element D to the bar E in the desired new position.

In some instances, when the rod F is first moved to the left so as to release the latch from engagement with the toothed bar E, the friction of engagement of the element D with the bar E may be small enough to permit the element D to be dragged toward the left without seating the latch nose in the seat 48. If this occurs, the rod F is pulled further to the left until the stop element D engages a limiting abutment pin 54 on the carriage end plate 5 which will prevent further movement of the stop element to the left and will assure setting of the latch nose in the seat 48 by a slight further movement of the rod. The element D will then be moved against the center stop in the manner already described. It will be observed that when the stop element D has been moved to the left and has engaged the abutment pin 54, the strap 49 on the right-hand end of the rod will engage the stop element D so as to limit movement of the rod to the left.

The modified form of rod G, shown in Figure 9, may be formed from a strip of metal or the like of uniform cross section throughout its length. The desired formation is given the bar by bending it at 55 to provide a deformed portion having a cam edge 56 corresponding to the cam edge 47 on the rod F, previously described. The deformed portion also is formed with a transversely extending seat 57 adapted to function similarly to the seat 48 in the rod F and the

extreme outer end of the rod G is turned downwardly as at 58 for engagement with the stop element D to limit movement of the rod F to the left.

5 The right margin stop D' is similar to the left margin stop D already described, and it therefore is considered unnecessary to describe in detail the parts of the right-hand stop D'. Similar or corresponding parts of the stops D 10 and D' are designated by similar reference characters, with the exception that the reference characters designating parts of the right-hand stop are primed. Thus, the U-shaped member 27' of the stop D' corresponds to the U-shaped member 27 of the stop D; the latch 32' corresponds to the latch 32, and so on. It will, of course, be understood that both stops D and D' 15 can be set manually when desired simply by depressing the finger knobs 39 and 39'.

20 The mechanism disclosed herein embodies the invention in a practical and its at present preferred form, but it will be understood that various changes may be made without departing from the invention as defined in the claims.

25 I claim:

1. In a typewriting machine, a frame, a carriage mounted thereon for letter spacing movements; a stop supported on the frame; a cooperating stop supported on the carriage, one of said stops being adjustable on its support in the direction of carriage letter spacing movement; a member normally disconnected from said adjustable stop mounted for movement longitudinally of said support; and means responsive to longitudinal movement of said member for releasably coupling said member to said adjustable stop for moving it along its support in the direction of letter spacing movement.

2. In a typewriting machine, a frame, a carriage mounted thereon for letter spacing movements; a stop supported on the frame; a cooperating stop supported on the carriage, one of said stops being adjustable on its support in the direction of carriage letter spacing movement; releasable means for locking said adjustably mounted stop in adjusted position on its support; a member mounted for movement longitudinally of the direction of adjusting movement of said adjustably mounted stop and engageable at will 40 with said releasable means for releasing the latter; and means for releasably coupling said member to said adjustably mounted stop for moving it along its support.

3. In a typewriting machine, a frame, a carriage mounted thereon for letter spacing movements; a stop supported on the frame, a cooperating stop supported on the carriage, one of said stops being adjustable on its support in the direction of carriage letter spacing movement; a latch for releasably holding said adjustable stop in position on its support; a stop adjusting member movable in the direction of adjustment of said stop on its support and being connectable with said stop for adjusting it along said support; said member including a cam for releasing said latch, and means for releasably coupling said member to said adjustably mounted stop for moving it along its support.

4. In a typewriting machine, a frame, a carriage mounted thereon for letter spacing movements; a stop supported on the frame; a cooperating stop supported on the carriage, one of said stops being adjustable on its support in the direction of carriage letter spacing movement; a latch for releasably holding said adjustable stop

in position on its support; and stop adjusting means movable in the direction of adjustment of said stop on its support and being connectable with said stop for adjusting it along said support, said means including a latch-releasing cam and 5 also including a part adapted to releasably interlock with said adjustable stop.

5. In a typewriting machine, a frame, a carriage mounted thereon for letter spacing movements; a stop supported on the frame; a cooperating stop supported on the carriage, one of said stops being adjustable on its support in the direction of carriage letter spacing movement; a latch for releasably holding said adjustable stop in position on its support; stop adjusting means 10 movable in the direction of adjustment of said stop on its support and being connectable with said stop for adjusting it along said support, said means including a latch-releasing cam and 15 also including a part adapted to releasably interlock with said adjustable stop; and means for limiting movement of said stop adjusting means relative to said bar-mounted stop.

6. In a typewriting machine, a frame, a carriage mounted thereon for letter spacing movements; a stop supported on the frame; a cooperating stop supported on the carriage, one of said stops being adjustable on its support in the direction of carriage letter spacing movement; releasable means on said adjustable stop for 25 holding said stop in adjusted position; and means movable in the direction of adjustment of said stop and including a cam for releasing said releasable means and a part adapted to releasably interlock with said releasable means for moving 30 the stop to adjusted position on its support.

7. In a typewriting machine, a frame; a carriage mounted thereon for letter spacing movements; a bar on said carriage extending in the direction of carriage letter spacing movements; 40 a stop on said frame; a cooperating stop mounted for adjustment along said bar; means for releasably holding said bar-mounted stop in adjusted position on said bar; and means movable lengthwise of the bar for adjusting the bar-mounted stop including a cam for releasing said releasable means and also including a part adapted to interlock releasably with a part on said bar-mounted stop for moving said stop along said bar.

8. In a typewriting machine, a frame; a carriage mounted thereon for letter spacing movements; a bar on said carriage extending in the direction of carriage letter spacing movements; a stop on said frame; a cooperating stop mounted for adjustment along said bar; means for 55 releasably holding said bar-mounted stop in adjusted position on said bar; means movable lengthwise of the bar for adjusting the bar-mounted stop including a cam for releasing said releasable means and also including a part 60 adapted to interlock releasably with a part on said bar-mounted stop for moving said stop along said bar; and means for holding said parts interlocked but being yieldable to permit unlocking thereof when the bar-mounted stop is pushed 65 against said frame-mounted stop.

9. In a typewriting machine, a frame, a carriage mounted thereon for letter spacing movements; a toothed bar on said carriage and extending in the direction of carriage letter spacing 70 movements; a stop on said frame; a cooperating stop mounted for adjustment on said bar; a latch on said bar-mounted stop having a nose engageable with selected teeth on said bar; a member mounted for movements longitudinally 75

- of the bar; a cam surface on said member engageable with said latch for disengaging said nose from the toothed bar; and means on said member adapted to connect releasably with said bar-mounted stop element for moving the latter longitudinally of the bar.
10. In a typewriting machine, a frame, a carriage mounted thereon for letter spacing movements; a toothed bar on said carriage and extending in the direction of carriage letter spacing movements; a stop on said frame; a cooperating stop mounted for adjustment on said bar; a latch on said bar-mounted stop having a nose engageable with selected teeth on said bar; a member mounted for movements longitudinally of the bar; a cam on said member connectable with said latch for disengaging said nose from said bar; and a seat on said member for receiving and releasably interlocking with a part on said bar-mounted stop.
15. In a typewriting machine, a frame, a carriage mounted thereon for letter spacing movements; a toothed bar on said carriage and extending in the direction of carriage letter spacing movements; a stop on said frame; a cooperating stop mounted for adjustment on said bar; a latch on said bar-mounted stop having a nose engageable with selected teeth on said bar; a member mounted for movements longitudinally of the bar; a cam on said member connectable with said latch for disengaging said nose from said bar; and a seat on said member for receiving and releasably interlocking with a part on said bar-mounted stop.
20. 11. In a typewriting machine, a frame, a carriage mounted thereon for letter spacing movements; a toothed bar on said carriage and extending in the direction of carriage letter spacing movements; a stop on said frame; a cooperating stop mounted for adjustment on said bar; a latch on said bar-mounted stop having a nose engageable with selected teeth on said bar; a spring for yieldably urging said latch nose to bar-engaging position; a member mounted for movement longitudinally of the bar; a cam on said member engageable with said latch nose for disengaging it from said bar against the urge of said spring; and a seat on said member adjacent said cam for receiving said nose after it has been disengaged from said bar to releasably interconnect the bar-mounted stop with said member for adjustment of the stop along the bar.
25. 12. In a typewriting machine, a frame, a carriage mounted thereon for letter spacing movements; a toothed bar on said carriage and extending in the direction of carriage letter spacing movements; a stop on said frame; a cooperating stop mounted for adjustment on said bar; a latch on said bar-mounted stop having a nose engageable with selected teeth on said bar; a spring for yieldably urging said latch nose to bar-engaging position; a member mounted for movement longitudinally of the bar; a cam on said member engageable with said latch nose for disengaging it from said bar against the urge of said spring; and a seat on said member adjacent said cam for receiving said nose after it has been disengaged from said bar to releasably interconnect the bar-mounted stop with said member for adjustment of the stop along the bar, said seat comprising a notch or recess in said member and having an inclined edge whereby the latch nose will be cammed out of said seat when the member is moved to press the bar-mounted stop against the frame-mounted stop.
30. 13. In a typewriting machine, a frame element; a carriage element mounted thereon for letter spacing movements; cooperating stops supported on said elements respectively, the support for one of said stops comprising a toothed bar extending in the direction of letter spacing movement of the carriage and on which the associated stop is slidably adjustable, said bar being longitudinally slotted inwardly from the face thereof on which the teeth are formed; a latch on said bar-mounted stop having a nose extending across the slot in the bar and being releasably engageable with selected teeth on the bar for maintaining said stop in adjusted position; a rod mounted for endwise movement in said slot; a cam face on said rod engageable with said latch nose for releasing the latch; and a seat on said rod for receiving said nose when thus released and for releasably coupling said bar-mounted stop to said rod.
35. 14. In a typewriting machine, a frame element; a carriage element mounted thereon for letter spacing movements; cooperating stops supported on said elements respectively, the support for one of said stops comprising a toothed bar extending in the direction of letter spacing movement of the carriage and on which the associated stop is slidably adjustable; a latch on said bar-mounted stop releasably engageable with selected teeth on the bar for maintaining said stop in adjusted position; a member mounted for movement along said bar; means on said member for releasing said latch; and a seat on said member adapted to receive a part connected to said bar-mounted stop for coupling said stop to said member.
40. 15. In a typewriting machine, a frame element; a carriage element mounted thereon for letter spacing movements; cooperating stops supported on said elements respectively, the support for one of said stops comprising a toothed bar extending in the direction of letter spacing movement of the carriage and on which the associated stop is slidably adjustable; a latch on said bar-mounted stop; a spring urging said latch to engagement with said bar between adjacent teeth thereof for maintaining said stop in adjusted position; a member mounted for movement along said bar; a cam on said member adapted to engage said latch and release it from said bar against the urge of said spring; and a seat on said member positioned to receive said latch under the urge of said spring to couple said member to said bar-mounted stop.
45. 16. In a typewriting machine, a frame element; a carriage element mounted thereon for letter spacing movements; cooperating stops supported on said elements respectively, the support for one of said stops comprising a toothed bar extending in the direction of letter spacing movement of the carriage and on which the associated stop is slidably adjustable, said bar being longitudinally slotted inwardly from the face thereof on which the teeth are formed; a latch on said bar-mounted stop having a nose extending across the slot in the bar and being releasably engageable with selected teeth on the bar for maintaining said stop in adjusted position; a rod mounted for endwise movement in said slot; a cam face on said rod engageable with said latch nose for releasing the latch; and a seat on said rod for receiving said nose when thus released and for releasably coupling said bar-mounted stop to said rod.
50. 17. In a typewriting machine, a frame element; a carriage element mounted thereon for letter spacing movements; cooperating stops supported on said elements respectively, the support for one of said stops comprising a toothed bar extending in the direction of letter spacing movement of the carriage and on which the associated stop is slidably adjustable, said bar being longitudinally slotted inwardly from the face thereof on which the teeth are formed; a latch on said bar-mounted stop having a nose extending across the slot in the bar and being releasably engageable with selected teeth on the bar for maintaining said stop in adjusted position; a rod mounted for endwise movement in said slot; a cam face on said rod engageable with said latch nose for releasing the latch; a seat on said rod for receiving said nose when thus released and for releasably coupling said bar-mounted stop to said rod; and
55. 75

means on said rod for limiting movement of the rod in both directions longitudinally of the bar.

18. In a typewriting machine, a frame element; a carriage element mounted thereon for letter spacing movements; cooperating stops supported on said elements respectively, the support for one of said stops comprising a toothed bar extending in the direction of letter spacing movement of the carriage and on which the associated stop is slidably adjustable, said bar being longitudinally slotted inwardly from the face thereof on which the teeth are formed; a latch on said bar-mounted stop having a nose extending across the slot in the bar and being releasably engageable with selected teeth on the bar for maintaining said stop in adjusted position; a rod mounted for endwise movement in said slot, a portion of said rod being disposed in said slot between the bottom of the slot and the roots of said teeth; and an enlargement on said bar extending at least to the tops of said teeth and comprising a cam engageable with said latch nose for releasing said latch.

19. In a typewriting machine, a frame element; a carriage element mounted thereon for letter spacing movements; cooperating stops supported on said elements respectively, the support for one of said stops comprising a toothed bar extending in the direction of letter spacing movement of the carriage and on which the associated stop is slidably adjustable, said bar being longitudinally slotted inwardly from the face thereof on which the teeth are formed; a latch on said bar-mounted stop having a nose extending across the slot in the bar and being releasably engageable with selected teeth on the bar for maintaining said stop in adjusted position; and a rod mounted for endwise movement in said slot, a portion of said rod being disposed in said slot between the bottom of said slot and the roots of said teeth, said bar having a deformed portion directed away from the bottom of said slot and extending at least to the tops of said teeth and comprising a cam engageable with said latch nose for releasing said latch.

20. In a typewriting machine, a main frame; a carriage mounted thereon for letter-spacing movements; a margin stop bar on said carriage; a stop on said main frame; a cooperating stop mounted on and for adjustment along said bar; means for releasably locking said bar-mounted stop in adjusted position on said bar; a member mounted for movement along said bar and being engageable with said locking means for unlocking said bar-mounted stop; a seat on said member adapted to receive the released locking means; and a spring for urging said locking means into said seat to couple said member and bar-mounted stop together for movement along said rod, said spring being yieldable when said bar-mounted stop is pushed against said frame-mounted stop for permitting unseating of said locking means.

21. In a typewriting machine, a frame; a carriage mounted thereon for letter spacing movements; a stop supported on the frame; a cooperating stop supported on the carriage, one of said stops being adjustable on its support in the direction of carriage letter spacing movement; means for releasably holding said adjustable stop in adjusted position on its support; a member mounted for movement with respect to said support and in the direction of letter spacing movement; and means carried by said member and being frictionally connectible to said adjustable stop for moving it along its support and being releasable from said adjustable stop when the latter is pressed against the other stop.

22. In a typewriting machine, a frame; a carriage mounted thereon for letter spacing movements; a toothed margin stop bar on said carriage; a relatively fixed stop on said frame; a stop slideable along said bar; a latch for releasably fixing said bar mounted stop in adjusted position on said bar; a member mounted for movement longitudinally of said bar; means on said member for releasing said latch; and means on said member for frictionally and releasably connecting the bar-mounted stop to the member for movement along said bar.

WILLIAM F. METZGER.
